CLAIM

The ornamental design for a pourer for a bottle, as shown and described.

DESCRIPTION

FIG. 1 is a perspective view of a pourer for a bottle in an open configuration showing my new design;

FIG. 2 is a front view thereof; the rear and side views being identical;

FIG. 3 is a bottom perspective view thereof;

FIG. 4 is a perspective view of the pourer for a bottle of FIG. 1 in a closed configuration; and,

FIG. 5 is a front view of FIG. 4; the rear and side views being identical.
